UNITED STATES PATENT OFFICE

2,546,603

METHOD OF ORNAMENTING COIL SPRING WRISTBANDS

Leroy H. Knibb, Chicago, Ill.

Application December 7, 1948, Serial No. 63,908

2 Claims. (Cl. 51—281)

1

The invention relates to the ornamentation of wristwatch bands or the like of the coil spring type, and more particularly to a machine for use in selectively forming recesses in one or more of the faces of the convolutions of the wire to produce the desired pattern on a preformed coil.

One object of the invention is to provide a machine for selectively deflecting convolutions of the coil for use in cutting recesses in the outer faces of the band to produce a desired pattern or design.

Another object of the invention is to provide an improved method for selectively forming recesses in the band for ornamentation.

Another object of the invention is to provide a machine for selectively deflecting convolutions of the coil for forming recesses in the outer faces of the band by which different patterns or designs may be produced.

Another object of the invention is to provide a machine of this character which is comparatively simple in construction and efficient in use.

Other objects will appear from the detailed description.

The invention consists in the several novel features which are hereinafter set forth and are more particularly defined by claims at the conclusion hereof.

In the drawings—

Fig. 1 is a plan view of a machine embodying the invention, parts being shown in section;

Fig. 2 is a longitudinal section taken on line 2—2 of Fig. 3;

Fig. 3 is a section taken on line 3—3 of Fig. 2;

Fig. 4 is a partial longitudinal section on an enlarged scale illustrating the deflector plates in their normal position and a coil positioned therein;

Fig. 5 is a similar view illustrating alternate convolutions of the band deflected into position for a recess-forming operation;

Fig. 6 is a section taken on line 6—6 of Fig. 5;

Fig. 7 is a horizontal section taken on line 7—7 of Fig. 6;

Fig. 8 is a transverse section taken on line 8—8 of Fig. 2, the band being omitted;

Fig. 9 is a plan illustrating an ornamental pattern with staggered rows of recesses;

Fig. 10 is a section similar to Fig. 5 illustrating the deflector plates arranged for deflecting alternate pairs of the convolutions of the coil; and

Fig. 11 is a plan of a portion of a band with recesses cut therein in staggered relation in alternate pairs of convolutions of the coil.

The machine of the invention is adapted for

2

use in ornamenting bands formed of an elongated resilient strip, such as spring wire pre-formed into a coil with convolutions having straight inner and outer portions 10 connected by semi-circular connecting bends 11. The band is usually provided with fittings at its ends for attachment to a wristwatch or the like. In practice, it is desirable to form or cut recesses in one or both of the straight portions of the convolutions for ornamental effect. It is also advantageous to form the recesses by cuts extending longitudinally by the band by suitable cutting tools or by grinding wheels. The invention provides a machine for selectively deflecting convolutions of the band from a coplanar or coaxial position for forming recesses in the deflected convolutions by a rectilinearly moving tool or grinding wheels traveling across the straight portions of the convolutions. The invention also provides for variations in the convolutions deflected for varying the pattern or design for different ornamental effects.

The invention is exemplified in a machine which comprises a base 29, upstanding ends 21, and sides 24 which are rigidly secured to form a rigid box-like supporting structure for the mechanism hereinafter described.

Before inserting the band into the machine, it is stretched to separate the convolutions of the coil and supported in stretched condition by spreader means which comprises a bar 27 and upstanding ribs 28 which are inserted between the convolutions and retain them spread apart during the recess-forming operation. The ribs 28 are slightly inclined transversely, conformably to the pitch angle of the straight portions 10 in one face of the coil. One purpose of spreading the convolutions apart is to prevent the accumulation of dust or cuttings on the coil during the recess-forming operation. The bar 27 of the spreader-means may be positioned endwise of the supporting structure by a stop 29 which is on one of the end-supports 21 (Fig. 4) and a pin 29a (Fig. 1) which is removably held in the opposite end-support 21. The upper bar 28 at said opposite end has a cutaway to permit the bar 27 to be inserted endwise from said opposite end when the pin 29a is removed from end-support 21 at said opposite end. When the bar 27 is inserted in its operative position, pin 29a will lock said bar against endwise movement. The spreader-means and the blank coil are pre-assembled for placement in the deflecting mechanism.

Deflector plates generally designated 30, in number corresponding to the number of convolu-

tions in the coil, are positioned between ends 21 of the supporting structure, fit between the sides 24, and extend transversely at a slight angle corresponding substantially to the pitch-angle of one of the straight portions 19 of the convolutions of the coil. Plates 30 are vertically slidable in the supporting structure and are spaced apart by ribs 31 on the inner faces of sides 24 correspondingly to the convolutions of the coil while it is held stretched by spreader-means. Each reflector plate 30 is adapted to receive and hold or grip one convolution of the coil. For this purpose each plate 30 is provided with curved notches 33 in which fit the opposite connecting bends 11 of one convolution of the coil. While the notches 33 are normally positioned they are aligned longitudinally of the supporting structure, so that the assembled coil and spreader-means can be inserted endwise through the series of plates 30 and positioned so that each convolution will be held or gripped in one of the plates 30, and so that when a deflector plate is lifted the convolution held therein will be deflected upwardly above the plane of the plates remaining in their normal position. Plates 30 are cut away as at 34 for clearing the spreader bar 27 during the lifting movements of the plates and to permit insertion of the spreader bar through the plates. Stop bars 36 secured to the sides 24 of the supporting structure limit the upward movement of plates 30.

For ornamenting the band with rows of recesses 40 formed in alternate convolutions of the wire coil, the convolutions in which the recesses are to be cut, are deflected upwardly above the plane of the other convolutions of the coil so that the recesses in the deflected convolutions may be cut by a gang of grinder wheels which travel transversely across the reflected convolutions. For ornamenting the band as illustrated in Fig. 9, with rows of staggered recesses in alternate convolutions of the wire coil, the intermediate convolutions are deflected upwardly for a second operation to cut the rows of staggered recesses in the deflected convolutions while the previously recessed convolutions are retained in a lower position. In this cutting operation, the machine may be magnetically held in different assigned positions on a suitable support for the rectilinear traverse of a series of grinding wheels or cutters across the upwardly deflected convolutions of the coil.

The deflector plates are operable to shift in series alternate convolutions of the coil. A pair of shafts 50 fit in and extend through holes 53 in one series of alternating plates 30 and are adapted to raise and lower said series of plates. A pair of shafts 51 fit in and extend through holes 54 in the intermediate series of plates 30 and are adapted to raise and lower said series of plates. The plates 30 which are fitted to and shiftable by shafts 50, are provided with clearance holes 56 around shafts 51 to permit said plates to move relatively to the plates operatively connected to shafts 51. Plates 30 which are fitted to and shiftable by shafts 51, are provided with clearance holes 55 to permit said plates and shafts 51 to move relatively to shafts 50.

The pairs of shafts 50 and 51 are selectively operable to raise and lower the deflector plates 30 operatively connected to said pairs of shafts, respectively. The shafts 50 are cross-connected for conjoint raising and lowering movements by bars 58 in which they are clamped by screws 60. The shafts 51 are cross-connected by a bar 62

in which they are clamped by screws 63. Bars 58 and 62 are selectively operable to raise or lower the deflector plates 30 by mechanism which includes a pair of cams 59 which are rotatably and coaxially mounted on studs 59^a which are screw-threaded into upstanding brackets 64 which are fixedly secured to the base 28. Each cam 59 is provided with an arm 65, and these arms are connected together by a lever bar 66 for conjoint operation of said cams. Bars 58 which connect the outer ends of shafts 50, are provided with studs 67 which extend into cam slots 68 in cams 59. Bars 62 are provided with studs 69 which extend through cam slots 70 in cams 59, respectively. When studs 67, 69 are positioned at the circumferential centers of slots 68 and 70, or in their neutral position, the plates 30 will be in longitudinal alignment or in their normal position. When cams 59 are rotated by operating bar 66 in one direction from their neutral position, one end portion of cam slots 68 will raise studs 67 and lift shafts 50 and the set of plates operatively connected thereto, and the diametrically opposite end portions of cam slots 70 will lower studs 69 and the alternate set of plates to the base 28. The convolutions of the coil held by the set of plates operatively connected to shafts 50 will then be deflected upwardly to above the plane of the convolutions of the coil gripped by the plates 30 which are operatively connected to shafts 51. When cams 59 are rotated in the opposite direction from their neutral position, one end portion of cam slots 70 will raise studs 69 and lift the set of plates operatively connected to shafts 51, and the diametrically opposite end portions of slots 68 will lower studs 67 and the plates operatively connected to shafts 50. This will deflect upwardly the convolutions of the coil which are gripped by shafts 51 for a recess-forming operation on said coil. A spring-pressed detent 72 is adapted to yieldingly seat in notches 73 in cams 59 to spot the cams in their neutral position and in positions for the alternate operations of the sets of plates 30. This exemplifies means for shifting the plates 30 into neutral position for the insertion of the coil and the placement of the spreader means in the plates and for alternately shifting the sets of plates operatively connected to pairs of shafts 50, 51 and deflecting the convolutions of the coil held by the respective sets of blades.

The operation will be as follows: The operating bar will be shifted into its neutral position so that all of the plates will be longitudinally aligned. A preformed blank coil will be stretched with the ribs 28 on bar 27 inserted between the convolutions of the coil to hold it stretched. When pin 29^a is removed, the bar 27 with the coil thereon will be inserted endwise until its first inserted end will abut against stop 29 on one of the end-supports 21. Pin 29^b is then replaced in opposite end-support 21 and the bar 27 will be locked against endwise movement and seated on bars 27. The lower straight portions of the convolutions will rest on bar 27 between ribs 28 and the convolutions will be aligned longitudinally. When the deflector plates are in neutral position, the assembled and stretched coil can then be inserted endwise through the cut-aways 34 in plates 30. The connecting bends 11 of the convolutions of the coil will be positioned in the opposed notches 33 in the plates, respectively. The bar 27 will facilitate the insertion of the coil in the plates 30. Each convolution

of the coil will then be held or gripped in one of the deflector plates 39 and be stationarily supported while said plates are in their normal position. Lever 66 will then be lifted from its normal position to shift cams 59 and lift shafts 50. The series of deflector plates 38 operatively connected to shafts 50, will deflect the convolutions held in said plates, as illustrated in Figs. 5 and 6, while the series of deflector plates operatively connected to shafts 51, will be lowered from their normal position. A gang of grinding wheels or cutting tools will be operated across the top of the straight portions 10 of the deflected convolutions on the line a—a of Fig. 5 to cut rows of recesses 40 in the deflected convolutions of the coil. Lever 66 will then be shifted to its neutral position to lower the deflected convolutions to their normal position. When it is desired to form rows of staggered recesses in the convolutions, the machine and the tools will be relatively shifted and set to cut the staggered recesses in the alternate set of convolutions, and lever 66 will be lowered from its neutral position to shift cams 59 so that cam slots 70 will lift shafts 51 and the deflector plates 38 operatively connected to said shafts and lower the plates operatively connected to shafts 50. This will deflect the convolutions between those which have been previously recessed. The recessing tools will then be operated to form recesses in the deflected convolutions in staggered relation to the previously formed recesses. After the recessing tools have been thus operated, lever 66 will be shifted to its neutral position and the recessed coil with the spreader plate will be removed from the machine for a succeeding operation. During the cutting operations the dust or cuttings will drop between the spaces in the stretched coil and between the plates 38, so that it will not obstruct the movement of the deflector plates. This exemplifies means for selectively shifting series of elements for deflecting one set of convolutions of the coil relatively to another set.

The deflector plates 38 are adapted to be differently arranged on shafts 50 and 51 for variation in the pattern of the recesses in the coil, for example, to form staggered recesses in alternating pairs of contiguous convolutions of the coil, as illustrated in Fig. 11. For this purpose alternating pairs of contiguous plates 38 are operatively connected to shafts 50 and 51, respectively. With the deflector plates thus arranged, the operation of shafts 50 will deflect alternating pairs of contiguous convolutions, as illustrated in Fig. 10, for forming rows of recesses in the deflected pairs of convolutions, and the operation of shafts 51 will deflect intermediate pairs of convolutions for forming recesses in staggered rows in the convolutions deflected by said shafts. The operation of the machine with this arrangement of plates will be the same as that hereinbefore described, except that the convolutions will be deflected in alternating pairs of contiguous convolutions, away from the intermediate

pairs. This exemplifies the manner in which the deflector plates may be re-arranged on the shafts 50, 51 in the supporting structure for variation in the recessing to produce different patterns or ornamental effects.

5 The invention exemplifies a simple and efficient machine for use in ornamenting preformed coils of resilient wire, which provides for selective deflection of the convolutions of the coil for cutting recesses in different patterns. The construction is simple, efficient, and results in accurate cutting of the wire to form desired patterns on the coil.

10 The invention also exemplifies an improved method of forming recesses in the band for ornamentation.

15 The invention is not to be understood as limited to the details described, since these may be modified within the scope of the appended claims 20 without departing from the spirit and scope of the invention.

Having thus described my invention, what I claim as new and desire to secure by Letters Patent is:

25 1. That improvement in ornamenting a pre-formed coil of resilient wire, which comprises: stretching the coil to spread apart the convolutions, supporting the convolutions of the coil, deflecting while the coil is stretched a group of 30 convolutions into a different plane from another group, and forming lines of recesses in one group of convolutions while the coil is stretched.

35 2. That improvement in ornamenting a pre-formed coil of resilient wire having substantially flat faces connected by curved bends, which comprises: stretching the coil to spread apart its convolutions, supporting the convolutions of the coil, alternately deflecting transversely of the coil, and while the coil is stretched, groups of 40 convolutions into an offset plane, and alternately cutting lines of recesses in the groups.

LERoy H. KNIBB.
